UNITED STATES PATENT OFFICE.

LUM SANG LOY, OF SAN FRANCISCO, CALIFORNIA, ASSIGNOR TO LEE WAY KING, OF SAN FRANCISCO, CALIFORNIA.

DESIGN FOR A TEA BASKET.

Application filed January 23, 1924. Serial No. 8,374. Term of patent 14 years.

To all whom it may concern:

Be it known that I, LUM SANG LOY, a citizen of the United States, residing in the city and county of San Francisco and State of California, have invented a new, original, and ornamental Design for a Tea Basket, of which the following is a specification, reference being had to accompanying drawing, forming part thereof.

The figure is a perspective view of a tea basket showing my new design.

I claim:

The ornamental design for a tea basket as shown.

LUM SANG LOY.
